DESIGN FOR A PLAYING CARD HOLDER OR SIMILAR ARTICLE

Ruth Miller, New York, N. Y.

Application February 6, 1945, Serial No. 117,784

Term of patent 3½ years

(Cl. D34—13)

To all whom it may concern:

Be it known that I, Ruth Miller, a citizen of the United States, residing at New York city, in the county of New York and State of New York, have invented a new, original, and ornamental Design for a Playing Card Holder or Similar Article, of which the following is a specification, reference being had to the accompanying drawing, forming part thereof.

In the drawing:

I claim:

The ornamental design for a playing card holder or similar article, substantially as shown.

RUTH MILLER.
